United States Patent Office.

ERNEST VON JEINSEN, OF OMAHA, NEBRASKA.

Letters Patent No. 105,146, dated July 5, 1870.

IMPROVEMENT IN SELF-ACTING LUBRICATOR FOR AXLE-BOXES.

The Schedule referred to in these Letters Patent and making part of the same.

To all whom it may concern:

Be it known that I, ERNEST VON JEINSEN, of Omaha, in the county of Douglas and State of Nebraska, have invented a new and improved Self-lubricating Axle-Box; and I do hereby declare the following to be a full, clear, and exact description thereof, which will enable those skilled in the art to make and use the same, reference being had to the accompanying drawing forming part of this specification, in which drawing—

Figure 1 represents a transverse section of this invention.

Figure 2 is a longitudinal section of the same.

Similar letters indicate corresponding parts.

This invention relates to an axle-box for locomotives or railroad cars, both shells of which are provided with bearing-strips, of felt, or other absorbent material, extending throughout their entire length, the absorbent bearing-strip in the lower shell being in contact with a wick, which is pressed up against it by a spring, and the lower end of which dips into an oil-reservoir formed in the bottom part of the axle-box in such a manner that the wick is constantly held in contact with the absorbent bearing-strip, notwithstanding the oscillations or changes in the position of the axle-box, and the journal of the axle is at all times supplied with the requisite amount of lubricating material as long as a sufficient supply is kept up in the oil-reservoir, and, furthermore, by the absorbent bearing-strips the lubricating material is uniformly distributed over the entire length of the journal.

In the drawing—

The letter A designates the upper, and the letter B the lower shell of an axle-box.

Each of these shells is provided with an absorbent bearing-strip, *a* or *b*, of felt, or other suitable material, said bearing-strips being inserted into grooves extending throughout the entire length, or nearly so, of the shells, as shown in fig. 2 of the drawing.

From the groove in the lower shell extends a hole,

c, which is countersunk below and serves to admit the upper end of a wick, *d*, which is attached to a spring, *e*, by which the same is constantly pressed up against the absorbent strip *b*.

The lower end of said spring is held in position by a guiding-piece, *f*, placed in the oil-reservoir, and retained in the proper relation to the lower shell by a spring, *g*.

The bottom end of the wick dips into a reservoir formed in the lower part of the axle-box, (not shown in the drawing,) and as the axle rises and falls, the spring *e* extends or contracts without allowing the wick to get out of contact with the absorbent strip.

By these means a constant supply of oil is transmitted from the oil-reservoir to the absorbent strip *b*, and by it transferred to the journal of the axle, and, as the journal revolves, the oil is carried up to the absorbent strip of the upper shell, and thus, by the two absorbent strips, the journal is uniformly lubricated throughout its entire length as long as a sufficient supply of oil is maintained in the reservoir.

What I claim as new, and desire to secure by Letters Patent, is—

1. The shells A B of an axle-box or lubricator, formed with grooves which receive absorbent strips of material, *a* and *b*, when combined and operating in connection with the wick *d* and spring *g*, substantially as described.

2. The countersunk hole *c* in the bottom of the shell B, receiving the end of a wick, *d*, which is pressed upward against the absorbent material *b* by the spring *e*, which is held in position by the guiding-piece *f* in the oil-reservoir, and operating in connection with the spring *g*, substantially as described.

This specification signed by me this 15th day of April, 1870.

ERNEST VON JEINSEN.
